METHOD OF DIATHERMIC TREATMENT BY MEANS OF HIGH FREQUENCY

Abraham Esau, Jena, Germany

Application June 16, 1933, Serial No. 676,195
In Germany January 21, 1928

11 Claims. (Cl. 128—1.3)

This invention relates to the treatment of abnormal physical conditions by diathermic waves generated by high frequency electro-magnetic means and has special reference to apparatus for controlling the application of such waves.

As set forth in my prior application for patent filed December 26, 1928 and bearing the Serial Number 328,509, eventuating July 18, 1933, in Patent No. 1,918,386, and of which this application is a continuation in part, I have made an improvement on the prior means employed wherein for diathermic purposes high frequency oscillations were used whose wave length ranged from a few hundred meters up to a few thousand meters and I have, in the aforesaid application, set forth the manner in which such wave lengths produced injurious effects on the body tissues.

In the present invention, I have provided a further improvement on previous methods wherein in a directed beam of high frequency oscillations having wave lengths not exceeding ten meters is used in such diathermic treatment and in this device, as in my prior device, the body under treatment is not allowed to function as ohmic resistance.

In the accompanying drawing, there is shown in a semi-diagrammatic manner an apparatus for carrying this invention into execution.

In this drawing, as one means for the production of the desired short waves, a source of electric current is here indicated as a battery 10. At 11 is a three element valve having the usual filament or cathode 12, grid 13 and plate or anode 14. A battery 15 has its terminals connected to the terminals of the filament or cathode by conductors 16 and one terminal of the battery 10 is connected to one of the conductors 16 by a conductor 17.

At 18 is a translating device, here shown as a dipole, for the production of electro-magnetic field oscillations and one terminal of this device is connected to the remaining terminal of the battery 10 by a conductor 19 which is also connected to the plate or anode 14 by a conductor 20. The remaining terminal of the device 18 is connected by a conductor 21 with the grid 13 and this grid is also connected to the remaining conductor 16, and thus to the cathode or filament 12, by a conductor 22. A choking coil 23 is interposed in the conductor 22.

At 24 is a wave reflector of a type suitable for reflecting the field waves emanating from the device 18. Preferably the reflector is of parabolic type and the device 18 is located at the focus of the reflector so that the waves are reflected as a beam of parallel rays from this reflector and may thus be directed to a desired location on the body of the person under treatment.

The arrangement is such that owing to the back coupling of the tube between the oscillating circuit through the device 18 and the grid circuit proper, undamped electrical oscillations are maintained through the device 18 whose period of natural vibration is not greater than that required for ultra-short waves of not more than ten meters length on account of the small internal capacities of the tube. Obviously, instead of the diagram shown, any other known arrangement for the generation of short waves of the length desired may be used.

Heretofore it has been the practice in carrying out diathermic treatments by means of high frequency to either place treatment electrodes in direct contact with the body part to be treated, with liability of injury to the patient, or to dispose the body part between and in spaced relation to the treatment electrodes. The latter method overcomes the objections to the direct contact method, but this latter method is sometimes also found objectionable, especially in the case of lengthy treatments as set forth in my aforesaid Patent No. 1,918,386, because of the liability of causing injurious effects upon operators or attendants exposed for undue periods to the uncontrolled rays within the region of the electrostatic field. These injurious effects may be minimized or overcome by converting the open field into a closed one by the use of a concentrating shield, as described in said patent, but the use of the shield is often awkward, uncomfortable and inconvenient to the patient and under some conditions may interfere with adjustment of the body part treated or itself be found difficult of adjustment to proper position. The present invention, however, allows the use of such a shield to be dispensed with and the body part of the patient to be properly disposed in the path of the wave beam and treated without inconvenience to the patient or operator or liability of injury to operator or attendant from exposure to the rays, since by the use of the reflector the rays are concentrated to the desired degree and projected in the form of a beam directly upon the part to be treated. Also by the use of a translating device having a natural period of vibration for producing an intense wave field of a frequency within a determined range found best suited for a specific character of treatment, maximum efficiency of operation is secured, since the treatment action may be directed and controlled with great precision.

I claim:

1. In a therapeutic apparatus, a dipole, a reflector adjacent said dipole directing the waves from the dipole in a definite direction, a source of current, a conductive connection between one element of said dipole and one side of the source of current, a vacuum tube containing a plate, a

grid and a heater filament, a second conductive connection connecting the remaining member of the dipole and said grid, a third conductive connection connecting the plate with the first conductive connection, a fourth conductive connection between the remaining side of the source of current and the second conductive connection and including a filament battery and resistance in series, and conductive connections from each 10 end of said filament to the fourth conductive connection on opposite sides of said filament battery.

2. Apparatus for diathermic treatment of a subject disposed in a trajectory zone of treatment by means of high frequency waves, comprising generating means for generating ultra-short waves suitable for producing internal heat in the subject to be treated, a path for said waves connected to said generating means and including a dipole for producing an intense field at a focal point in sufficiently close proximity to the subject to produce the thermic effect, and means associated with said dipole for directing the waves as a beam through said zone and directly 25 against the subject.

3. Apparatus for diathermic treatment of a subject disposed in a trajectory zone of treatment by means of high frequency electro-magnetic waves, comprising a short wave generating means for generating electric waves having a length not greater than ten meters, and including a translating device for locally producing an intense wave field in said trajectory zone and means to direct the waves of the field as a beam 30 through the zone directly against the subject to be treated.

4. Apparatus for diathermic treatment of a subject disposed in a trajectory zone of treatment by means of high frequency electro-magnetic waves, comprising a short wave generating means having a natural period of vibration for generating electric waves having a length not greater than ten meters, a path for said waves connected to said generating means and including a dipole for producing an intense wave field in said trajectory zone at a point spaced from but located in close proximity to the subject, and means to direct the waves of the field as a beam through the zone directly against the subject to 50 be treated.

5. Apparatus for diathermic treatment of a subject by means of high frequency waves, comprising a translating device arranged and operative to produce an electro-magnetic field in close proximity to the subject to be treated, means connected to said translating device for generating and transmitting therethrough short electric waves of a length suitable for producing internal heat in the proximately disposed subject, 60 and reflecting means associated with said translating device and arranged to reflect the waves from the translating device in a treatment beam directly against the subject.

6. Apparatus for diathermic treatment of a subject by means of high frequency electromagnetic waves, comprising means for generating short electric waves of a length suitable for producing internal heat in a subject to be treated, a path for said waves connected to said 70 means and including a translating device for producing an intense wave field in sufficiently close proximity to the subject to produce the thermic effect, and reflecting means associated

with said translating device and arranged to reflect waves from the translating device in a treatment beam directly upon the subject.

7. Apparatus for diathermic treatment of a subject disposed in a trajectory zone of treatment by means of high frequency electro-magnetic waves, comprising means for generating electric waves of a length suitable for producing internal heat in the subject to be treated, a path for said waves connected to said means and including a dipole for producing an intense wave field at a focal point in said zone, and a parabolic reflector for said waves disposed at said focal point and having the dipole located at its focus and operative to reflect the waves through 15 said zone as a beam directly upon the subject.

8. Apparatus for diathermic treatment of a subject disposed in a trajectory zone of treatment by means of high frequency waves, comprising a short wave generating means having a natural period of vibration for generating ultra-short electric waves of a length suitable for producing internal heat in the subject to be treated, a path for said waves connected to said means and including a translating device for producing an intense wave field at a focal point in sufficiently close proximity to the subject to produce the thermic effect, and reflecting means associated with said translating device and arranged to reflect the waves from the translating device 20 through said zone as a beam directly upon the subject.

9. Apparatus for diathermic treatment of a subject disposed in a trajectory zone of treatment by means of high frequency waves, comprising a short wave generating means for generating ultra-short electric waves of a length suitable for producing internal heat in the subject to be treated, a path for said waves connected to said means and including a dipole for 35 producing an intense wave field at a focal point in sufficiently close proximity to the subject to produce the thermic effect, and reflecting means associated with said dipole for reflecting the waves through said zone as a beam directly upon the subject.

10. Apparatus for diathermic treatment of a subject disposed in a trajectory zone of treatment by means of high frequency waves, comprising a short wave generating means for generating ultra-short electric waves of a length suitable for producing internal heat in the subject to be treated, a path for said waves connected to said means and including a dipole for producing an intense wave field at a focal point 50 in sufficiently close proximity to the subject to produce the thermic effect, and a parabolic reflector associated with the dipole for reflecting the waves through said zone as a beam directly upon the subject.

11. Apparatus for diathermic treatment of a subject disposed in a trajectory zone of treatment by means of high frequency waves, comprising a short wave generating means for generating short waves having a length not greater than ten meters and including a translating device operative to produce an intense electromagnetic field in said trajectory zone, and reflecting means associated with said translating device and arranged to reflect the waves from the translating device in a treatment beam directly against the subject.
